CLAIM

The ornamental design for an adjustable breakout wrench for blasthole drill rods of different diameters, as shown and described.

DESCRIPTION

FIG. 1 is a perspective view of an adjustable breakout wrench for blasthole drill rods of different diameters in accordance with the present invention.

FIG. 2 is a top view of an adjustable breakout wrench for blasthole drill rods of different diameters in accordance with the present invention.

FIG. 3 is a rear view of an adjustable breakout wrench for blasthole drill rods of different diameters in accordance with the present invention.

FIG. 4 is a bottom view of an adjustable breakout wrench for blasthole drill rods of different diameters in accordance with the present invention.

FIG. 5 is a back view of an adjustable breakout wrench for blasthole drill rods of different diameters in accordance with the present invention.

FIG. 6 is a right side view of an adjustable breakout wrench for blasthole drill rods of different diameters in accordance with the present invention.

FIG. 7 is a left side view of an adjustable breakout wrench for blasthole drill rods of different diameters in accordance with the present invention; and,

FIG. 8 is a partial exploded perspective view of an adjustable breakout wrench for blasthole drill rods of different diameters in accordance with the present invention, showing a removed Top Plaque.

The long dash-short dash broken lines of FIG. 8 depict the path for assembly of the exploded components and forms no part of the claimed design.
